UNITED STATES PATENT OFFICE.

JOHN RITZENTHALER, OF MOUNT VERNON, NEW YORK.

CLEANING CLOTH.

Application filed November 28, 1922. Serial No. 603,834.

To all whom it may concern:

Be it known that I, JOHN RITZENTHALER, a citizen of the United States, and a resident of Mount Vernon, in the county of Westchester and State of New York, have invented a new and Improved Cleaning Cloth, of which the following is a full, clear, and exact description.

This invention relates to a cleaning cloth, and an object of the invention is to provide a cleaning cloth having a generous area provided with means whereby the cloth can be effectively and simply attached or gripped in either hand to be manipulated without losing the effect of any of the area of the cloth.

The invention is illustrated in the drawings, of which—

Figure 1 is an elevation of the cloth fitted to a hand.

Fig. 2 is a plan view.

Fig. 3 is a section taken on the line 3—3 of Fig. 2.

The form of the invention shown in the drawings is a preferred form, although it is understood that modifications in the construction and arrangement of the parts and in the character of the materials used may be adopted without departing from the spirit of the invention.

The invention as illustrated in its preferred form in the drawings comprises preferably a sheet of flexible material 1 suitable for cleaning purposes, and preferably some material such as chamois. It is of ample area to provide a generous amount of cleaning surface, and on one face there is attached thereto an auxiliary sheet of material

of any suitable type which is sewed to the cleaning cloth 1 along three sides, 3, 4 and 5, and also along a curved line simulating in outline the outline of the fingers of a hand. This auxiliary piece of cloth thus sewed to the cleaning cloth 1 thus acting as a sort of pocket into which the hand may be placed to achieve the more efficient and thorough manipulation of the cleaning cloth and also to protect the hand. It will be noted that the outline of the hand shown particularly in Fig. 2 has two thumbs 7 and 8, adapting this cloth to be placed on either hand with equal facility. It will be noted, moreover, that the area of the cloth 1 extends generously in every direction beyond the outlines of the pocket member, and because the material is flexible, the cloth can be gathered in the hand as desired, making its manipulation very efficient and easy whereby the maximum area of the cloth can be made use of in cleaning.

What I claim is:—

A cleaning cloth which comprises a relatively large sheet of flexible cleaning material, an auxiliary sheet of stiffer material disposed on one face thereof and sewed thereon along three sides to form a pocket for the hand, the area of the flexible cleaning cloth being much greater than the area of the pocket member, said auxiliary sheet being also sewed to the cleaning cloth along area within the edges thereof to simulate the outline of the hand, said sewed outline being provided with two thumbs to facilitate the attachment of the cloth to either hand of the operator.

JOHN RITZENTHALER.
